UNITED STATES PATENT OFFICE.

ALEXANDER WINTON AND HAROLD B. ANDERSON, OF CLEVELAND, OHIO, ASSIGNEES TO
THE WINTON MOTOR CARRIAGE COMPANY, OF CLEVELAND, OHIO.

CARBURETER.

No. 925,973.

Specification of Letters Patent. Patented June 22, 1909.

Application filed April 9, 1907. Serial No. 367,209.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Carbureters, of which the following is a specification, reference being had therein to the accompanying drawing.

10. This invention relates to improvements in carbureters, for furnishing an explosive mixture to explosive engines, and pertains to the type which is made the subject-matter of our application #323,117, pending concurrently herewith, in which the slowly moving volumes of air are subjected to an exposed body of volatile fluid for surface carburation, and the rapidly-moving volumes of air subjected to spray carburation.
20. The object of the present improvement is to provide a deflector within the air passage adjacent the exposed body of oil, and to control the movement of this deflector, whereby the carbureter is made capable of adjustment, and therefore adapted for regulation to suit the particular motor to which it is applied.

In the accompanying drawings, Figure 1, is a sectional view showing one form of our improvement. Fig. 2, is a section at right angles to Fig. 1. Fig. 3, is a modification.

Referring now to the drawings, 1 is a fluid chamber in which there is located a float 2, and this float 2 controls an inlet valve 3 for the purpose of maintaining a fluid level in the chamber 1. The operation of this construction is so well understood that any further explanation of it is unnecessary.

An air passage 4 extends across the chamber 1 and has its end 5 communicating with the motor. The usual throttle or valve 6 may be used for controlling the passage of the mixture from the carbureter to the motor, and thereby controlling the motor.

45. As shown, the lower wall or bottom 7 of the air passage 4 extends downward to a plane below the maintained oil level of the chamber 1, and is provided with an oil orifice 8 through which the oil passes from the chamber to the passage-way 4, and in this way a body of fluid is maintained within the passage-way for the surface carburation of the slowly moving volumes of air. The rapidity with which the oil is permitted to

flow through the orifice 8 may be controlled by means of an adjustable valve 9.

It is desirable to have the slowly moving volumes of air directed close to the exposed body of oil in this type of carbureter, and for this purpose a deflector 10 is placed within the air passage and at a point at or in front of the exposed body of fluid. As here shown, this deflector is hinged at its upper end, and is declined in the direction of the air currents.

In the form shown in Fig. 1 the deflector is made of sufficient weight to maintain the position shown in Fig. 1 against the very slowly moving volumes of air, as when the motor is cut down and running very slow. When necessary, the deflector is provided with one or more portions 10' to increase its weight. In this instance, the throttle 6 will be almost closed so that the current of air passing through the passage-way will not be sufficient to lift the deflector. To permit air to pass by the deflector it is recessed as shown at 11. In this way the slowly moving volumes of air are caused to pass close to and against the exposed fluid, and to be properly carbureted. When, however, the throttle is open wider and the volumes of air are passing through the passage so rapidly that the body of fluid is not maintained within the passage, then the current is sufficient to lift the deflector, and the carbureter then acts on the spray principle by drawing the fluid through the orifice 8.

For the purpose of controlling the action of the deflector when the carbureter is working as a spray carbureter, means is provided for regulating the distance that the deflector shall swing open. This may be accomplished in many ways, and in Fig. 1 it is accomplished by means of an adjustable member or screw 12 which passes through the top of the air passage with its inner end in the path traveled by the deflector. This provides a very simple means for controlling the opening action of the deflector.

In Fig. 3 a modification is shown in which the deflector 10' is made without any recess at its lower edge, and its closing action is controlled by an adjustable screw 13. In this way the deflector is made adjustable in respect to the slowly moving volumes of air, as well as in respect to the rapidly moving volumes of air. In a carbureter having this

principle the air passage can be so constructed for a motor of a given size that a deflector, or other controlling means, is not necessary, but when the carbureter is to be built for universal use (within reasonable limits) then it is desirable to have means for adjusting the control of the passing currents of air.

It will be understood by those skilled in this art that an adjustable deflector can be constructed in various ways, and we do not therefore desire to limit ourselves to the construction here shown.

Having thus described this invention, what we claim and desire to secure by Letters Patent, is:—

1. A carbureter comprising an air passage provided with a fluid inlet orifice, means for maintaining a body of fluid within the passage by gravity feed through said orifice for slowly moving volumes of air, the orifice being restricted to cause the rapidly moving volumes of air to suck and thereby spray the fluid drawn through said orifice, a freely movable deflector in the air passage actuated by the passing currents of air, and positive limiting means positively controlling the opening movement of the deflector and the maximum air capacity of said passage.
2. A carbureter of the type described having an air passage, a deflector therein and

pivoted at its upper end, said deflector declined in the direction of the moving currents of air, and adjustable members located at opposite sides of the deflector for the purpose of adjustably limiting its movement in both directions.

3. A carbureter comprising an air-passage provided with a fluid inlet orifice, means for maintaining a body of fluid within the passage by gravity feed through said orifice for slowly moving volumes of air, the orifice being restricted to cause the rapidly moving volumes of air to suck and thereby spray the fluid drawn through said orifice, a freely movable deflector in said air-passage opened by the passing currents of air, and an adjustable limiting means positively but adjustably controlling the opening movement of the deflector and thereby adjustably controlling the velocity of the air passing through said air-passage to adjustably control the surface and spray carburetion of the passing air.

In testimony whereof we affix our signatures in presence of two witnesses.

ALEXANDER WINTON.
HAROLD B. ANDERSON.
